Singer Manufacturing Company, Elizabeth,
N. J., a corporation of New Jersey

Application September 2, 1939, Serial No. 293,155

28 Claims.

(Cl. 112—16)

This invention relates to sewing machines and more particularly to a sewing machine of the type having feeding wheels or "cups" for supporting and feeding the work to the stitching mechanism.

An object of the invention is to provide improved operating mechanism for the stitch-forming devices so that the sewing machine can be operated at high speed with a minimum of vibration and with little attention by the operator as to the lubrication of the operating mechanism.

A further object of the invention is to provide a sewing machine of the above type wherein the supporting members for the looper and spreader are confined to simple oscillatory or rocking movements about the axes of the supporting members so that oil-tight joints may be formed between the supporting members and the frame of the machine, thereby permitting the use of the well-known splash-lubricating system for oiling the mechanism within the frame.

Another object of the invention is the provision of an improved work-supporting and feeding mechanism including feed-cups located exteriorly of and supported by the machine-frame for advancing the fabric sections past the stitching mechanism at a uniform rate.

With the above and other objects in view, as will hereinafter appear, the invention comprises the devices, combinations, and arrangement of parts hereinafter set forth and illustrated in the accompanying drawings of a preferred embodiment of the invention, from which the several features of the invention and the advantages attained thereby will be readily understood by those skilled in the art.

In the accompanying drawings, Fig. 1 is a front elevation of a sewing machine embodying the invention with the outer feed-cup removed and a portion of the overhanging bracket broken away.

Fig. 2 is a left side elevation with a portion of the machine-frame broken away to show the adjustable mounting for the uncurling device.

Fig. 3 is a vertical transverse sectional view taken through the machine-frame and illustrating the main-shaft and some of the connections actuated thereby.

Fig. 4 is a vertical longitudinal sectional view taken through the machine-frame and illustrating the needle-bar mechanism and the feeding mechanism.

Fig. 5 is a top plan of the machine with the cover-plate removed showing the belt-drive for the outer feed-cup.

Fig. 6 is an enlarged view in elevation of the

pivotedly mounted feed-cup supporting lever for the outer feed-cup.

Fig. 7 is a horizontal sectional view taken through the machine-frame and illustrating the angular arrangement of the supporting members for the looper and spreader.

Fig. 8 is a bottom plan view of the machine with the lower cover-plate removed, showing the clutch and gear-drive for the feed-cups.

Fig. 9 is a bottom plan view of the clutch-actuating lever.

Figs. 10 and 11 are horizontal top sectional views taken substantially midway of the heights of the feed-advance clutch and the retrograde motion prevention clutch, showing the details of construction.

Fig. 12 is an enlarged view in elevation of the uncurling device used on the machine.

Fig. 13 is a left side view of Fig. 12.

Fig. 14 is a right side view of Fig. 12.

Fig. 15 is a fragmentary view of Fig. 12, showing the two latching detents which maintain the uncurling device in either operative or retracted position.

Fig. 16 represents a section taken substantially along the line 16—16, Fig. 12.

Fig. 17 is a disassembled perspective view showing the various elements of the uncurling guide latching device and the means for releasing the same.

Fig. 18 is a sectional view taken substantially along the line 18—18, Fig. 13, showing some of the details of the uncurling guide supporting means.

Frame and general structure

Referring in detail to the drawings, the present illustrated embodiment of the invention includes a machine-frame 1 having a base-portion or standard 2 and a laterally projecting overhanging bracket 3. Formed integral with the base-portion 2 and disposed beneath the overhanging bracket 3 is an extension 4 and a supporting lug 5, the latter sustaining the inner feed-cup 6 of the feeding mechanism and the extension providing a housing for some of the actuating connections for the inner feed-cup 6. Cooperating with the inner feed-cup 6 is an outer feed-cup 7 which depends from the overhanging bracket 3. Removably secured upon the bracket 3 is a cover-plate 8 which is secured by means of a screw 9.

Adjacent the top of the base-portion 1 is a horizontal partition 10 which divides the machine-frame into a splash-lubrication compartment 11 and a belt compartment 12, see Figs. 3

and 4. The splash-lubrication compartment 11 is closed at the bottom by means of a plate 13 secured by screws 14 and sealed by a gasket 15. As shown in Fig. 1, the machine is adapted to rest upon resilient pads P, of rubber, felt or the like, interposed between the plate 13 and the top of a table T, sidewise movement of the machine being limited by the resilient cushions C disposed in holes in the table T and secured to the machine base by wing-nut bolts B. This resilient mounting for the machine absorbs vibrations which would otherwise be transmitted to the table.

Disposed in the splash-lubrication compartment 11 transversely of the machine-frame is a main-shaft 16 journaled in bushings 17, Fig. 3, fixed 15 in flanged sleeves 18 secured by screws 19 in bosses 20 cast in the base 2. Mounted on the opposite ends of the main-shaft 16 are the usual balance-wheels 21 each having a belt-groove 22. Each flanged sleeve 18 is formed with an oil-port 23 in register with a slot 24 in the boss 20 and an oil inlet port 25 in the bushing 17, whereby oil is introduced into the shaft bearing. To prevent leakage of oil, the main-shaft 16 at its opposite ends is provided with spiral grooves 26 which feed the excess oil in the shaft bearing back into the splash-lubrication compartment 11. In addition to this oil-guard, the flanged sleeve 18 is provided with an undercut circular recess 27 entered by a reduced portion 28 of the balance-wheel 21. Formed in the reduced portion 28 are several circular oil-collecting grooves 29. In the event that some oil should leak onto the balance-wheel 21 this oil is collected in the grooves 29 and is thrown off by centrifugal force into the 35 undercut recess 27 and is returned into the splash-lubrication compartment 11 by a return port 30 formed in the lower portion of the flanged sleeve 18.

The main-shaft 16, as shown in Figs. 3 and 7, is formed with a crank, in addition to having secured thereto three eccentrics, whereby all the connections within the compartment 11 are actuated.

From Fig. 4, it will be seen that the connections actuated by the main-shaft 16 and extending below the same dip into oil, whose normal level is shown by the line L in Fig. 4, contained in the base of the machine. These connections, during the operation of the machine, splash the oil throughout the lubrication compartment 11 of the machine and thereby thoroughly lubricate the mechanism contained therein. The level of the oil can be inspected from time to time preferably through a transparent window 31 having thereon a horizontal line 32 indicating the correct level of the oil.

Located in the belt compartment 12, see Fig. 5, is a conventional clip-belt 33 for actuating the outer feed-cup 7, the pivotally mounted supporting lever 34 for the outer feed-cup 7, and a lighting attachment 35. The belt compartment 12 is not opened to the splash-lubrication compartment 11 so that the oil-laden atmosphere in the latter compartment does not find its way onto the stitch-forming instrumentalities or the feed-cups and contaminate the work.

From the above description, it will be understood that there is provided a machine-frame divided into two compartments, one of which is oil-tight and houses all the actuating mechanism operating at a high rate of speed, while the other of which is opened to the atmosphere and houses some of the actuating mechanism operating at a slower rate of speed. The pri-

mary advantage of such a construction is that the mechanism operating at high speed can be splash lubricated, while the mechanism operating at slow speed need not be splash lubricated. Further, it facilitates design and manufacture of the machine in that the elements of the machine projecting from the compartment which is separated from the oil-tight compartment and having a lateral motion, need not be fitted with a more or less complicated oil-seal to prevent the leakage of oil upon the stitch-forming and feeding mechanisms.

Needle-bar mechanism

Referring to Figs. 3 and 4 it will be observed that the needle-bar mechanism comprises a needle 36 fixed in the needle-clamp 37 secured upon a horizontally disposed reciprocating hollow needle-bar 38 journaled in bushings 39 and 40 fixed in the machine-frame. To effect a stripping of the oil from the needle-bar 38 as it reciprocates in the bushing 39, the bearing surface thereof has an annular recess 41 cut therein, which recess at its bottom opens into an oil-return groove 42 in the bushing 39 which directs any excess oil collected in the recess 41 back into the splash-lubrication compartment 11.

The needle-bar 38 intermediate its ends has clamped thereto by means of a screw 43 a collar 44 provided with an upstanding guide-lug 45 adapted to slide in a guideway between gibs 46 secured to the bottom of the horizontal partition 10 by screws 47. The function of the guide-lug 45 is to provide means for preventing the needle-bar 38 from turning in its bearings as the same is reciprocated. Depending from the collar 44 is a lug 48 connected by a link 49 to the upper limb of a rock-lever 50 having an elongated hub 51, see Fig. 7, journaled between collars 52 upon a fulcrum rod 53 fixed in spaced lugs 54 formed upon the machine-frame 1. Connected to the lower limb of the lever 50 is a pitman 55 which is connected at its other end to a crank 56 formed in the main-shaft 16.

From the above, it will be obvious that rotation of the main-shaft 16 imparts to the needle-bar 38, through the connections just described, a reciprocating motion in time with the other stitch-forming instrumentalities later to be described. As shown in Fig. 4, the rear wall of the machine-frame is provided with a removable screw-plug 57 which can be removed to permit assembly of the needle-bar in its bearings.

Looper-mechanism

Referring particularly to Figs. 3, 4 and 7, the looper 58, which is of the threaded type, is timed so that it seizes the thread-loop cast out by the needle 36 during the beginning of the needle-return or withdrawal stroke, thereby enchaining the needle-thread-loop with the thread passing through the eye of the looper 58.

The looper 58 is secured in a clamp 59 fastened upon the outer end of a supporting shaft 60 journaled for oscillation in an angularly disposed elongated bushing 61 fixed in the machine-frame 1. Clamped upon the inner end of the supporting shaft 60 is one end of a rock-lever 62 having at its other end a ball 63 and an extended guide-pin 64, the ball 63 being received in the socketed upper end of a pitman 65 formed at its lower end with a split strap 66 adapted to embrace a ball eccentric 67 fastened upon the main-shaft 16. To prevent the pitman 65 from turning, there is secured to the upper end-portion thereof

a forked member 68 which straddles the pin 64 on the rock-lever 62.

The function of the looper 58, as indicated briefly above, is, first, to seize the thread-loop cast out by the needle 36, thereby enchaining the same with the thread carried by the looper, and secondly, to position that portion of thread carried by the looper and adjacent the looper-eye so that the looper-thread can be engaged by a spreader which presents the looper-thread-loop to the needle for entrance by the latter. In the machine disclosed these two steps are effectively carried out by a simple oscillation of the looper 58 about the longitudinal axis of the supporting shaft 60. In order that the movement of the looper 58 may be reduced to a minimum, the longitudinal axis of the supporting shaft 60, see Fig. 7, is angularly arranged at an acute angle with respect to a vertical plane passing through the axis of the needle-bar 38. As distinguished from prior "cup-feed" machines, the angular arrangement of the looper-supporting shaft 60 simplifies the requisite motions imparted to the looper to accomplish stitch-formation. It will be understood that the looper point moves in a single plane and that only oscillatory movements need be imparted to the looper, instead of both movements of oscillation and lateral bodily movements as in many prior machines.

Referring to Fig. 4, it will be observed that the longitudinal axis of the looper-supporting shaft is disposed in a substantially horizontal plane. This position of the looper-supporting shaft 60 is of added advantage over the inclined supporting shaft of existing machines particularly in connection with lubrication of the shaft 60, in that oil splashed upon the connections at the inner end of the shaft does not travel by gravity toward the outer end thereof and contaminate the looper or the thread carried thereby. It is of course essential in machines of the "cup-feed" type that no oil shall find its way onto the stitch-forming instrumentalities or the feed-cups, and any means used to prevent such formation of oil improves the machine.

Spreader mechanism

Cooperating with the looper 58 and operating to spread the thread-loop presented by the looper for entrance by the needle 36 prior to its penetration of the fabric is a spreader 69, see Fig. 7. The spreader 69 forked at its free end is secured in a clamp 70 fastened upon the outer end of a supporting shaft 71 journaled in an angularly disposed elongated bushing 72 fixed in the machine-frame 1. Clamped upon the inner end of the supporting shaft 71 is a rock-lever 73 formed at its other end with a ball 74 and an extended pin 75. The ball 74 is received in the socketed upper end of a pitman 76 whose lower end is formed with a two-part strap 77 embracing a ball eccentric 78 fast upon the main-shaft 16. To steady the pitman 76, there is secured to the upper end-portion thereof a forked member 79 which straddles the pin 75 on the rock-lever 73.

The only function of the spreader 69 is to distend the looper-thread-loop so that the needle 36 will enter the same immediately before it penetrates the fabric. In accomplishing stitch-formation, the needle 36 passes through the fabric and at the beginning of its return stroke casts a thread-loop which is seized by the looper 58. The looper 58, having seized the needle-thread-loop and thereby enchaining the same

with the looper-thread, carries its own thread over the edge of the fabric where the looper-thread is engaged by the spreader 69 and a loop thereof distended downwardly in position for entrance by the needle 36 on its next work-penetrating stroke. In view of the angular arrangement of the spreader-supporting shaft 71, see Fig. 7, the motion required of the spreader is only an oscillatory motion of relatively small arc about the longitudinal axis of the supporting shaft 71. It will be seen that the spreader point also only moves in a single plane.

Inasmuch as the motions of the looper 58 and the spreader 69 are simple rocking movements, it can be understood that oil-tight joints may be made between the bushings 61 and 72 and the frame of the machine. The angular or convergent arrangement of the looper-supporting shaft 60 and the spreader-supporting shaft 71 is of decided utility in that the only motions required of the looper 58 and the spreader 69 are movements of oscillation. The use of such simple movements for the stitch-forming instrumentalities permits a high speed of operation with a minimum amount of vibration. Preferably the needle-bar 38, looper-supporting shaft 60 and spreader-supporting shaft 71 all have their longitudinal axes disposed in parallel planes (see Figs. 3 and 4), which in the machine illustrated are horizontal.

It has been successfully demonstrated that if a three-thread seam is required it is only necessary to replace the spreader with an eye-pointed threaded looper, and the machine as modified will produce a three-thread seam efficiently.

Feeding mechanism

The work is adapted to be intermittently fed through the machine in a vertically disposed position by means of the inner feed-cup 6 and the outer feed-cup 1. Referring particularly to Figs. 3 and 4, it will be seen that the inner feed-cup 6 is secured by screw 80 upon the upper reduced end-portion of a vertical feed-shaft 81 which is journaled in spaced bushings 82 and 83 fixed in the frame-lug 5 and the extension 4, respectively. Forming a housing for the vertical feed-shaft 81 is a relatively thin stationary tube or sheath 84 of which the upper end is fixed in the lug 5 and the lower end is fixed in the extension 4. The tube 84 serves as a guard for preventing the work from becoming wound upon the feed-shaft 81 as the latter is rotated and also, since the tube has a tight fit in the extension 4, the oil in the machine-frame 1 may rise in the tube 84 to the same level as the oil in the machine-frame, thereby lubricating the lower-bearing for the feed-shaft 81. The upper bearing is lubricated by hand (Fig. 4) through a central bore 85 and radial duct 86, the oil being distributed throughout the length of the bearing by the spiral oil-groove 87 cut into the feed-shaft 81.

The feed-shaft 81 has fastened upon its lower end-portion a spur gear 88 which meshes with a second spur gear 89 secured to the lower end of a feed-actuating shaft 90 journaled within the splash-lubrication compartment 11. The feed actuating shaft 90 is intermittently turned by a common form of one-way clutch 91 having an actuating-arm 92 connected by a link 93 to the lower end of an angle lever 94 journaled upon a stationary fulcrum-stud 95 fixed in a lug 96 integral with the machine-frame 1. The angle lever 94 is oscillated upon the fulcrum-stud 95

by an adjustable feed-eccentric 97 through the pitman connection 98. Access to the adjustable eccentric 97 may be had by removing the screw-plug 99 in the machine-frame 1. The provision of the adjustable eccentric permits the amount of turning movement imparted to the feed-cups 6 and 7 to be varied in accordance with the stitch-length desired.

From Fig. 3, it will be observed that the fulcrum-stud 95 is threaded into the lug 96 and is held against turning by a set-screw 100. To prevent movement of the hub of the elbow lever 94 lengthwise of the fulcrum-stud 95, a collar 101 is secured upon the inner end of the fulcrum-stud 95.

Referring now to Figs. 4 and 5, the feed-actuating shaft 90 has secured upon its upper end a notched belt-pulley 102 which is connected by a common form of clip-belt 33 to a second, or outer, notched belt-pulley 104 fastened upon the upper end of a depending feed-shaft 105 supporting at its lower end the outer feed-cup 7. The two belt-pulleys 102 and 104 are preferably constructed of a soft material, such as fiber or the like, to minimize wear and noise. The depending feed-shaft 105 is journaled in spaced bearings provided in the opposite ends of a stationary sheath 106 formed at its lower end with a flange 107 for supporting the usual needle-guide 108, and at its upper end clamped by screw 109 in the split end 110 of the pivotally mounted feed-cup supporting lever 34. From the above description, it will be understood that the two feed-cups 6 and 7 are intermittently driven simultaneously to advance the material in one direction past the stitching mechanism, and that the amount of movement imparted to the feed-cups per reciprocation of the needle is controlled by the adjustable feed eccentric 97.

Considering in detail the construction of the one-way clutch 91 (Figs. 4, 9, 10 and 11), it will be seen that the clutch comprises a housing 111 secured to the feed-actuating shaft 90 by set screws 112 and formed with spaced circular chambers or cavities 113 and 114. Cavity 113 houses that part of the clutch which imparts to the feed-cups their work-advancing movements, while cavity 114 houses that part of the clutch which prevents retrograde movement of the feed-cups. From Figs. 9 and 10 it will be seen that the actuating-arm 92 is rigidly fastened by means of three screws 115 to the bottom of a clutch-member 116 disposed in the cavity 113. The clutch-member is preferably formed with three suitable undercuts or recesses 117 providing inclined surfaces 118. Disposed in each of the recesses 117 is a relatively short cylinder or roller 119 which is engaged by a plunger 120 backed by a coil-spring 121, the plunger 120 acting to force the said roller toward the narrow end of the recess and wedge the same between the inclined surface 118 and the periphery of the cavity 113. In order to increase the life of the clutch, each inclined surface is fitted with a hardened steel wear-plate 122, and in order to distribute the wear across a substantial area of the surface of each wear-plate the center of the cavity 113 is eccentric to the longitudinal axis of the feed-actuating shaft 90 an amount equal to E, shown clearly by the two dot-and-dash lines connecting Figs. 10 and 11. This eccentricity permits the rollers 119 to travel in and out of the recesses 117, and in different relative positions of the clutch member 116 and

the housing 91 the rollers 119 contact different points along the surface of the wear-plates 122.

As indicated above, that part of the clutch which prevents retrograde movement of the feed-cups 6 and 7 is housed in cavity 114, see Figs. 4 and 11. The elements of this part of the clutch, with the exception of the locking clutch member 123, are duplicates of the work-advancing part of the clutch above described and therefore need no further description. The locking clutch member 123, see Fig. 4, is formed with a vertical sleeve 124, the bore of which is slightly larger in diameter than the size of the feed-actuating shaft 90. The sleeve 124 is held against turning in a lug 125 by a screw 126 threaded into said lug. In operation, as the actuating arm 92 is oscillated by the adjustable eccentric 97, the work-advancing or lower portion of the clutch 91 functions to intermittently turn the feed-cups in a direction to advance the work past the stitching mechanism, while the upper portion of the clutch 91 functions to prevent retrograde motion of the feed-cups.

Feed-cup separating mechanism

To facilitate the introduction of the work between the two feed-cups, means is provided whereby the outer feed-cup 7 can be shifted away from the inner feed-cup 6 whenever desirable. This means comprises the feed-cup supporting lever 34 which, as previously described, has clamped in its split forward end 110 the sheath 106 in which is journaled the feed-shaft 105. The feed-cup supporting lever 34, Figs. 4 and 5, adjacent its forward end is formed with two spaced bearing lugs 127 and 128 which are apertured to receive pivot studs 129 and 130. Pivot-stud 129 is secured by screw 131 in a supporting bracket 132 fastened by screws 133 upon the bottom wall of the belt compartment 12 and pivot-stud 130 is secured by screw 134 in a boss 135 cast integral with the machine-frame 1. The two bearing lugs 127 and 128 are spaced to provide a clearance for the clip-belt 33.

At the inner end of the feed-cup supporting lever 34 (see Figs. 4 and 5) there is formed an offset lug 136 and at right angles to the main body of the supporting lever 34 a stop-arm 137 adapted to be received between two adjustable stop-bars 138 and 139, which limit the extent of movement of the outer feed-cup 7 toward and away from the inner feed-cup 6. It will be observed in Fig. 4 that the upper stop-bar 138 is threaded upon the adjusting screw 140 and is guided by the second adjusting screw 141, while the lower stop-bar 139 is threaded upon the second adjusting screw 141 and guided by the first adjusting screw 140. By having the upper stop-bar 138 adjustable, the outer feed-cup 7 may be initially set at various distances from the inner feed-cup 6 depending upon the thickness of the material being sewn. After the stop-bar 138 has been correctly set, the lower stop-bar 139 can be adjusted to limit movement of the outer feed-cup in a direction away from the inner feed-cup. In order to facilitate assembly, the two adjusting screws 143 and 141 are reduced at their lower ends and set into apertures 142 drilled in the machine-frame, the screws 140 and 141 being maintained seated in these apertures 142 by the cover-plate 8 which rests upon the flanges 143 formed upon the heads of the adjusting screws 140 and 141.

Referring now to Fig. 3, it will be seen that the offset lug 136 provided at the inner end of the

feed-cup supporting lever 34 is apertured and dished, as at 144, to receive the semi-spherical nut 145 threaded upon the upper end of a control rod 146 connected at its lower end preferably by a chain to a knee-control or foot-treadle (not shown). The control-rod 146 extends through a tubular housing or sheath 147 which at its lower end is pressed into an aperture in an upstanding boss 148 integral with the bottom plate 13 and at its upper end extends through an aperture in the wall 10 of the machine-frame. The housing 147 provides an oil-seal and eliminates leakage of oil from the splash-lubrication compartment 11.

Means is provided for maintaining the outer feed-cup in its lowered or operative position and this means comprises a coil-spring 149 surrounding the control rod 146, the upper end of the spring bearing against the bottom of the offset lug 136 on the feed-cup supporting lever 34 and the lower end of the spring bearing on a washer 149 at the top of a tubular spacer member 150 within the housing 147. The bottom of the tubular spacer member 150 is in engagement with the top of an adjusting sleeve 151 threaded into the boss 148. The adjusting sleeve 151 at its lower end is formed with a knurled head 152 and has threaded upon its shank a locking nut 153 for securing the adjusting sleeve in any set position. From the above description it will be understood that the coil-spring 149 yieldingly maintains the stop-arm 137 in contact with the upper stop-bar 138 which initially positions the outer feed-cup 7 a definite distance from the inner feed-cup 6, and that the tension of the coil-spring 149 can be regulated by the adjusting sleeve 151.

It will be understood from the above description taken in connection with the accompanying drawings that there has been provided in a cup-feed sewing machine a feed-cup separating mechanism which is fully housed within the machine-frame, without any of the component elements thereof being exposed to view. Access may be had to the majority of the individual elements of the feed-cup separating mechanism by removal of the cover-plate 8 on the overhanging bracket 3.

Lighting attachment

In a machine of the type disclosed wherein the stitch-forming instrumentalities, feed-cups and a fabric-guide are necessarily crowded into a relatively small space, it is decidedly advantageous to have a sufficient amount of light directed to the vicinity of the stitching point so that the operator may observe the character of the stitching and the position of the work as it passes through the machine.

In the present case, the machine-frame 1 (see Fig. 2) is preferably formed with an inclined cavity 154 directly beneath the laterally projecting overhanging bracket 3. Disposed in the cavity 154 is a conventional lamp-socket 155 which is secured in position preferably by means of a clamp or strap 156 held in place by a screw 157 threaded into the machine-frame. Detachably secured in the socket 155 is a low-voltage incandescent lamp 158, the free end of which is disposed outside of the cavity 154 and beneath the junction of the overhanging bracket 3 and the base-portion 2.

Current is supplied to the lamp from a suitable source by an insulated conductor 159 which extends through a tubular conduit 160 passing ver-

tically through the splash-lubrication compartment 11. Projecting from the bottom of the conduit 160 is the usual flexible BX covering 161 protecting the insulated conductor 159. For a more detailed description of the present lighting attachment reference may be had to my copending divisional application Serial No. 307,725, filed Dec. 6, 1939.

If it is desired, the upper portion of the lamp 158 can be painted black or otherwise shaded to minimize the glare of the lamp.

Uncurling guide

When the machine illustrated is used for certain operations, such as seaming hosiery, it is fitted with an uncurling guide which uncurls and directs the edges of the fabric preparatory to stitching. The uncurling guide shown in the accompanying drawings forms the subject of my United States Patent No. 2,256,881, issued Sept. 23, 1941.

The uncurling guide, as shown in Figs. 1 and 2, is located directly in front of the feed-cups 6 and 7. The guide includes a central guiding plate 162 terminating at its upper end in a supporting shank portion 163. Disposed on opposite sides of the guiding plate 162 adjacent its lower end are uncurlers 164 and 165 yieldingly pressed by springs 166 against the faces of the guiding plate. Each of the uncurlers is of regular construction and further description is therefore not necessary. The uncurling guide is mounted upon a support including a horizontal plate 167, an angle bracket 168 and a vertical plate 169, whereby the guide is adapted to be adjusted laterally of the plane of the fabrics, toward or away from the feed-cups and raised or lowered relative to the stitching point. In Fig. 2 it will be seen that the horizontal plate 167 is formed with a longitudinal rib 170 adapted to be received in a groove in the overhanging bracket 3 and is held in set position by a clamping screw 171 passing through an elongated aperture 172 in the overhanging bracket 3. The aperture 172 is elongated so that the horizontal plate 167 can be adjusted laterally.

At its forward end the plate 167 is formed with a transverse rib 173 adapted to be received in a groove formed in the horizontal limb of the angle-bracket 168. Extending through an elongated transverse aperture 174 (see Fig. 18) in the horizontal limb of the angle bracket 168 is a clamping screw 175 which secures the angle bracket in adjusted position on the horizontal plate 167. When the screw 175 is released the angle bracket 168 can be shifted in a line parallel to the line of feed of the work, and then the screw may be tightened for securing said bracket in its adjusted position.

Formed in the vertical limb of the angle bracket 168 is an elongated vertical aperture 176 through which extends the clamping screw 177 threaded into the vertical plate 169. To maintain the plate 169 in correct vertical position relative to the vertical limb of the angle-bracket 168, the latter is provided with a vertical groove 178 (see Fig. 18) which is entered by a rib 179 on the vertical plate 169. Vertical adjustment of the plate 169 is effected by means of an adjusting bolt 180 annularly grooved to receive the horizontal projection 181 formed on the angle bracket 168 and threaded into a lug 182 integral with the vertical plate 169. When the clamping screw 177 is released and the adjusting bolt 180 is turned, it will positively raise and lower the vertical plate

169, and then the screw 177 can be tightened for holding the plate 169 in its adjusted position.

Referring now to Figs. 16 and 17, it will be seen that the supporting shank portion 163 of the central guiding plate 162 is formed with a bearing aperture 183 through which projects a cylindrical boss 184 formed upon a stationary locking disk 185. The locking disk is rigidly fastened face to face to the vertical plate 169 by a bolt 186, with the shank 163 of the central guiding plate 162 interposed between the vertical plate and the locking disk. To permit the central guiding plate 162 to turn freely upon the boss 184, the width of said boss is slightly in excess of the thickness of the central guiding plate.

To positively hold the uncurling guide in set positions, the locking disk 185 is formed with three notches 187, 188 and 189. Cooperating with these notches are two pivotal latches 190 and 191 biased toward each other by a coil-spring 192 connected by screws 193 to the free ends of the latches. The two latches are controlled by the lever 194 having oppositely directed faces 195 and 196 and fulcrumed upon a stud 197 threaded into an ear 198 formed on the shank 163 of the central guiding plate 162. The stud 197, in addition to supporting the lever 194, also provides the pivot for the two latches 190 and 191, the adjacent ends of which are apertured, as at 199 and 200, to receive the stud 197.

Referring now to Fig. 12, it will be understood that the uncurling guide is shown in full lines in its normal operative position. In such position the latch 190 is disposed in the notch 187 in the locking disk 185, while the latch 191 rides on the periphery of the locking disk, the latch 190 being held in the notch 187 by the coil-spring 192. When it is desired to shift the uncurling guide out of operative position and into the position shown in dotted lines in Fig. 12, the lever 194 is moved in a counterclockwise direction (Fig. 12) about the stud 197, and the initial movement of the lever 194, which movement is independent of the central guiding plate 162, raises the latch 190 out of the notch 187. When the latch is entirely clear of the notch, the lever 194 and the central guiding plate 162 move as a unit, turning the guide about the axis of the cylindrical shoulder 184 on the locking disk 185 until the latch 191 registers with and enters the notch 188 in the locking disk. During this turning of the guide the latches 190 and 191 ride upon the periphery of the locking disk 185, the coil-spring 192 being sufficiently strong so that pressure on the lever 194 in a counterclockwise direction will not tend to lift the latch 190 off the periphery of the locking disk 185, but will effect a substantially rigid connection between the lever 194 and the guide.

When it is desired to return the uncurling guide to operative position, such as shown in full lines in Fig. 12, the lever 194 is turned in a clockwise direction, thereby first moving the latch 191 out of the notch 188 and, secondly, turning the guide about the boss 184 until the latch 190 registers with and enters the notch 187 in the locking disk 184.

From the above description, it will be apparent that an uncurling guide has been provided having means including two latches controlled by a single guide-shifting lever for positively locking the guide in or out of operative position.

When threading the needle or the looper, or when adjusting or renewing any of the stitch-forming instrumentalities, it is desirable to have

the uncurling guide shifted to a position such that it will not interfere. To provide for this, the locking disk 185 is formed with a third notch 189 adapted to receive the latch 191. In order to swing the guide so that the latch 191 may enter the notch 185, it is first necessary to shift the guide into the position illustrated in dotted lines in Fig. 12. The operator must then hold the guide stationary and at the same time move the lever 194 toward the guide, or in a clockwise direction, thereby to disengage the latch 191 from the notch 188. After this disengagement is accomplished, a pressure on the guide in a counterclockwise direction will swing the guide to bring the latch 191 into register with the notch 189. When it is desired to return the guide to operative position, a downward pressure on the lever 194 will disengage the latch from the notch 189 and permit the guide to be swung about its supporting boss 184.

From the foregoing description considered in connection with the accompanying drawings, the construction, arrangement of parts and several advantages of my improved sewing machine will be clearly and fully understood. It will be understood that the form, construction and arrangement of the elements employed may be varied, and the privilege is reserved of resorting to all such legitimate changes therein as may be fairly embodied within the spirit and scope of the appended claims.

It will be appreciated that one of the attainments of the present invention is the development of a stitch-forming mechanism for a cup-feed sewing machine, whereof the thread-handling implements complementary to the usual needle are secured to carriers or supporting shafts 60 and 71 which are relatively convergent (see Fig. 7) toward the implements carried thereby and which are confined to oscillatory movements about their longitudinal axes. With this convergent arrangement only simple oscillatory movements of the two thread-handling implements 58 and 69 are required to assist the needle in proper stitch-formation. The simplified motions of the thread-handling implements can be produced through the use of mechanism susceptible of good balance, permitting the operation of the machine at high rates of speed, in the order of 5000 to 5500 stitches per minute, with a minimum of vibration. Also the simple motions imparted to the looper and spreader do not have any adverse thread-pulling or take-up influence on the sewing threads during their concatenation or during the setting of the stitches, with the result that the stitches are not prematurely set on the stitch-finger, but are formed with a uniform tightness sufficient to produce a relatively compact and neat seam.

Having thus set forth the nature of the invention, what I claim herein is:

1. A sewing machine having, in combination, a frame formed with a closed lubrication compartment, feed-cups located exteriorly of and supported by said frame for sustaining and feeding fabric sections in a vertical plane, stitch-forming devices including two oscillatable elements at least one of which carries a thread, an actuating shaft extending through said closed lubrication compartment, supporting rock-shafts for said oscillatable elements extending through one of the walls of said closed lubrication compartment and having an oil-tight connection therewith, the axes of said rock-shafts being disposed in a substantially horizontal plane and ar-

ranged angularly to each other, and means within said closed lubrication compartment for connecting said rock-shafts to said actuating shaft for moving said oscillatable elements so that their extremities operate in single planes only.

2. A sewing machine having, in combination, a frame, feed-cups having vertical axes exteriorly of and supported by said frame for sustaining and feeding fabric sections, stitch-forming devices including a needle and two oscillatable elements for producing stitches in said fabric sections, an actuating shaft journaled in said frame, a reciprocator rod supporting said needle and movable in a vertical plane containing the axis of each of the feed-cups, supporting members for said oscillatable elements each penetrating said frame at an acute angle to the vertical plane containing the axes of the feed-cups, and means connecting the supporting members of said stitch-forming devices to said actuating shaft for imparting operative movements to said devices.

3. A sewing machine having, in combination, a frame, feed-cups having vertical axes exteriorly of and supported by said frame for sustaining and feeding fabric sections, stitch-forming devices including a needle and two oscillatable elements for producing stitches in said fabric sections, an actuating shaft journaled in said frame, a reciprocator rod supporting said needle and movable in a vertical plane containing the axis of each of the feed-cups, supporting members for said oscillatable elements each arranged at opposite sides of and each at an acute angle to the vertical plane containing the axes of the feed-cups, and means connecting the supporting members of said stitch-forming devices to said actuating shaft for imparting operative movements to said devices.

4. In a sewing machine, a frame including a standard and a laterally projecting overhanging hollow bracket, a main-shaft journaled in said standard, a feed-actuating shaft also journaled in said standard and having one end thereof extending into said overhanging hollow bracket, means connecting said main-shaft to said feed-actuating shaft for imparting turning movements in one direction to the latter, means for preventing retrograde movements of said feed-actuating shaft, a shaft depending from said overhanging hollow bracket and carrying at its lower end a feed-cup, a belt within said hollow bracket for connecting said depending shaft with said feed-actuating shaft, a second feed-cup cooperating with said first feed-cup, a shaft supported by said standard and carrying said second feed-cup, and means connecting said last named shaft to said feed-actuating shaft, whereby the two feed-cups are simultaneously and positively turned to advance the work through the machine.

5. In a sewing machine, a frame including a standard and a laterally projecting overhanging hollow bracket, a main-shaft journaled in said standard, a feed-actuating shaft also journaled in said standard and having one end thereof extending into said hollow bracket, a one-way clutch mounted upon the feed-actuating shaft and operatively connected to said main-shaft, a pivotally mounted supporting lever disposed within said hollow bracket, a shaft depending from one end of said pivotally mounted supporting bracket and carrying at its lower end a feed-cup, a connection within said hollow bracket for connecting said depending shaft with said feed-actuating shaft, a second feed-cup cooperating with said first feed-cup, a shaft supported by

said standard and carrying said second feed-cup, and means connecting said last named shaft to said feed-actuating shaft, whereby the two feed-cups are simultaneously and positively turned to advance the work through the machine.

6. In a sewing machine, a frame including a standard formed with a closed lubrication compartment and a laterally projecting overhanging bracket formed with a belt compartment, a main-shaft journaled in said standard and extending through said lubrication compartment, a feed-actuating shaft also journaled in said standard and having one of its end portions projecting into the closed lubrication compartment and its opposite end projecting into the belt compartment in said overhanging bracket, means connecting said main-shaft to said feed-actuating shaft for imparting turning movements in one direction to the latter shaft, a shaft depending from said overhanging bracket and carrying at its lower end a feed-cup, a belt within said belt compartment for connecting said depending shaft with said feed-actuating shaft, a second feed-cup cooperating with said first feed-cup, a shaft supported by said standard and carrying at its upper end said second feed-cup and at its lower end projecting into the closed lubrication compartment in said standard, and means operatively connecting said last named shaft to said feed-actuating shaft.

7. In a sewing machine, a frame including a standard formed with a closed lubrication compartment and a laterally projecting overhanging bracket formed with a belt compartment, a main-shaft journaled in said standard and extending through said lubrication compartment, a feed-actuating shaft also journaled in said standard and having one of its end portions projecting into the lubrication compartment and its opposite end projecting into the belt compartment, means including a clutch assembly for connecting said main-shaft to said feed-actuating shaft for imparting turning movements in one direction to the latter shaft, a pivotally mounted supporting lever disposed within the belt compartment in said overhanging bracket, a shaft supported by and depending from one end of said pivotally mounted supporting bracket and carrying at its lower end a feed-cup, a belt within said belt compartment for connecting said depending shaft with said feed-actuating shaft, adjustable stop-means located within the belt compartment and accessible for adjustment outside of said belt compartment for limiting movement of said pivotally mounted supporting lever, a second feed-cup cooperating with said first feed-cup, a shaft supported by said standard and carrying at its upper end said second feed-cup and at its lower end projecting into the closed lubrication compartment in said standard, and means operatively connecting said last named shaft to said feed-actuating shaft.

8. A sewing machine having, in combination, a frame, feed-cups exteriorly of and supported by said frame for sustaining and feeding fabric sections, stitch-forming devices including a needle and two complementary oscillatable elements cooperating therewith for producing stitches in said fabric sections, an actuating shaft journaled in said frame, a reciprocator rod supporting said needle and movable in a single line, supporting shafts for said oscillatable elements each journaled in said frame at opposite sides of and each at an acute angle to a vertical plane containing the line of movement of the needle-supporting

rod, and means connecting the supporting shafts and the needle supporting rod to said actuating shaft for imparting operative movements to said stitch-forming devices.

9. A sewing machine having, in combination, a frame, feed-cups exteriorly of and supported by said frame for sustaining and feeding fabric sections, stitch-forming devices including a needle and two complemental oscillatable elements co-operating therewith for producing stitches in said fabric sections, an actuating shaft journaled in said frame, a needle-bar carrying said needle and movable endwise in a substantially horizontal plane, supporting members for said oscillatable elements sustained in substantially horizontal planes by said frame and at least one of which is arranged at an angle to a vertical plane containing the line of movement of said needle-bar, and means connecting the supporting members of said stitch-forming devices to said actuating shaft for imparting operative movements to said devices.

10. A cup-feed sewing machine comprising, a frame including a standard and a lateral bracket, feed-cups exteriorly of and supported by said frame for sustaining and feeding fabric sections, stitch-forming devices including a needle, looper and spreader adapted for cooperation above said feed-cups, an actuating shaft journaled in the standard of said frame, a needle-carrying bar journaled for endwise reciprocation in said standard, a looper-carrying bar journaled for oscillatory movements only about its longitudinal axis in said standard above the level of said needle-carrying bar, a spreader-carrying bar also journaled for oscillatory movements only about its longitudinal axis in said standard above the level of said needle-carrying bar, the longitudinal axes of the needle-carrying bar, looper-carrying bar, and spreader-carrying bar being disposed in parallel planes, and means connecting the aforementioned respective bars to said actuating shaft for imparting operative movements to said stitch-forming devices.

11. A sewing machine having, in combination, a frame, feed-cups exteriorly of and supported by said frame for suspaining and feeding fabric sections, stitch-forming devices including a needle, looper and spreader adapted for cooperation above said feed-cups, an actuating shaft journaled in said frame, a substantially horizontal needle-carrying bar journaled for endwise reciprocation in said frame, a substantially horizontal looper-carrying shaft journaled for oscillation about its longitudinal axis in said frame above the level of said needle-carrying bar, a substantially horizontal spreader-carrying bar also journaled for oscillation about its longitudinal axis in said frame above the level of said needle-carrying bar, the longitudinal axes of the looper-carrying bar and spreader-carrying bar being arranged in a relative angular relation to each other, and means connecting the needle-carrying bar, the looper-carrying bar and the spreader-carrying bar to said actuating shaft for imparting operative movements to said stitch-forming devices.

12. Stitch-forming mechanism for a cup-feed sewing machine having a frame provided with a lubricant compartment, including, a needle having operative movements outside of said compartment, mechanism disposed within said compartment for actuating said needle, a pair of thread-handling implements complemental to said needle in the formation of stitches, carrier-members for

said implements extending through a wall of said frame defining said lubricant compartment above the level of said needle, said carrier-members being relatively convergent toward the implements carried thereby and confined to oscillatory movements about fixed axes, and actuating mechanism disposed within said compartment for oscillating said carrier-members.

13. The combination set forth in claim 12 in which the angle of convergence between the carrier-members is an acute angle.

14. In a sewing machine, a frame including a standard having a base and a laterally projecting overhanging hollow bracket, stitch-forming devices, a main-shaft journaled in said frame, feed-cups located exteriorly of said frame for sustaining and feeding fabric sections, shafts carrying at their extremities said feed-cups, means operatively connecting said feed-cup supporting shafts to said main-shaft for rotation in one direction, means including a lever pivoted within said laterally projecting overhanging hollow bracket for sustaining one of said feed-cups for movement toward and away from said other feed-cup, and manually controlled means connected to said lever for separating said feed-cups to facilitate the introduction and removal of the fabric sections between said feed-cups, said manually controlled means being housed within said frame and operable through the base of said standard.

15. In a sewing machine, a frame including a standard having a base and a laterally projecting overhanging hollow bracket, stitch-forming devices, a main-shaft journaled in said frame, feed-cups located exteriorly of said frame for sustaining and feeding fabric sections, a shaft depending from said overhanging hollow bracket and carrying one of said feed-cups, a second shaft arranged substantially parallel to said first-mentioned shaft and carrying the other of said feed-cups, means operatively connecting said feed-cup carrying shafts to said main-shaft for rotation in one direction, means including a lever pivoted within said overhanging hollow bracket for supporting said depending feed-cup carrying shaft for limited movement toward and away from said other feed-cup, manually controlled means connected to said lever for separating said feed-cups to facilitate the introduction and removal of the fabric sections between said feed-cups, said manually controlled means being housed within said frame and operable through the base of said standard, and adjustable stops accessible for adjustment outside of the frame for limiting the extent of relative movement between said feed-cups.

16. In a sewing machine, a frame including a laterally projecting overhanging hollow bracket and a standard provided with a closed lubrication compartment, stitch-forming devices, a main-shaft journaled in said standard and penetrating said closed lubrication compartment, feed-cups located exteriorly of said frame for sustaining and feeding fabric sections, a shaft depending from said overhanging hollow bracket and carrying one of said feed-cups, a second shaft arranged substantially parallel to said first-mentioned shaft and carrying the other of said feed-cups, means operatively connecting said feed-cup carrying shafts to said main-shaft for rotation in one direction, means including a lever pivoted within said overhanging hollow bracket for supporting said depending feed-cup carrying shaft for limited movement toward and away from said other feed-cup, manually controlled means

connected to said lever for separating said feed-cups to facilitate the introduction and removal of the fabric sections between said feed-cups, said manually controlled means adapted to be housed within said frame and including a connection extending through the lubrication compartment in said standard and accessible from beneath the latter, and oil-sealing means preventing the escape of oil from said closed lubrication compartment where said connection penetrates the walls of said compartment.

17. In a sewing machine, a frame including a laterally projecting overhanging bracket and a standard provided with a closed lubrication compartment closed at its bottom by a detachable plate, stitch-forming devices, a main-shaft journaled in said standard, feed-cups located exteriorly of and beneath said overhanging bracket, a shaft depending from said overhanging bracket and carrying one of said feed-cups, a second shaft substantially parallel to said first mentioned shaft and carrying the other of said feed-cups, means operatively connecting said feed-cup carrying shafts to said main-shaft for turning movement in one direction, means including a lever pivoted to said overhanging bracket for supporting said depending feed-cup carrying shaft for limited movement toward and away from said other feed-cup, manually controlled means adapted to be housed within said frame and including a connection extending through the lubrication compartment in said standard and accessible from beneath the latter, and a sheath fixed in the detachable plate of said standard and extending through said lubrication compartment to surround said connection and prevent the egress of oil from the lubrication compartment.

18. A sewing machine comprising, a frame including a standard and a laterally projecting overhanging hollow bracket, a main-shaft journaled in said standard, feed-cups located exteriorly of and located beneath said overhanging hollow bracket, stitch-forming devices cooperating above the level of said feed-cups to seam fabric sections, a shaft depending from said overhanging hollow bracket and carrying one of said feed-cups, a second shaft arranged substantially parallel to said first mentioned shaft and carrying the other of said feed-cups, means operatively connecting said feed-cup carrying shafts to said main-shaft for rotation in one direction, a lever pivoted within said overhanging hollow bracket for supporting said depending feed-cup carrying shaft for limited movement toward and away from said other feed-cup, means for biasing said feed-cups into work-clamping relation, a control-rod connected to said lever and housed within said standard and accessible from beneath the latter for separating said feed-cups for the insertion and removal of the fabric sections, a stop-arm provided on said pivoted lever, and adjustable stop-means within said overhanging hollow bracket for cooperation with said stop-arm to limit the extent of relative movement of said feed-cups.

19. A sewing machine comprising, a frame including a standard and a laterally projecting overhanging hollow bracket, a main-shaft journaled in said standard, feed-cups located exteriorly of and located beneath said overhanging hollow bracket, stitch-forming devices cooperating above the level of said feed-cups to seam fabric sections, a shaft depending from said overhanging hollow bracket, and carrying one of

10 said feed-cups, a second shaft arranged substantially parallel to said first mentioned shaft and carrying the other of said feed-cups, means operatively connecting said feed-cup carrying shafts to said main-shaft for rotation in one direction, a lever pivoted within said overhanging hollow bracket for supporting said depending feed-cup carrying shaft for limited movement toward and away from said other feed-cup, a control-rod connected to said lever and mounted for endwise movement in a sleeve adjustably supported in said machine-frame, said control-arm adapted to be manually operated to separate said feed-cups for the insertion and removal of the fabric sections, and means including a spring for biasing said feed-cups into work-clamping relation, the action of said spring adapted to be regulated by the adjustable sleeve guiding said control-rod.

20. A sewing machine comprising, a frame including a standard and a laterally projecting overhanging hollow bracket, a main-shaft journaled in said standard, feed-cups located exteriorly of and located beneath said overhanging hollow bracket, stitch-forming devices cooperating above the level of said feed-cups to seam fabric sections, a shaft depending from said overhanging hollow bracket and carrying one of said feed-cups, a second shaft arranged substantially parallel to said first mentioned shaft and carrying the other of said feed-cups, means operatively connecting said feed-cup carrying shafts to said main-shaft for rotation in one direction, a lever pivoted within said overhanging hollow bracket for supporting said depending feed-cup carrying shaft for limited movement toward and away from said other feed-cup, a control-rod connected to said lever and mounted for endwise movement in a sleeve threaded into said machine-frame, said control-rod adapted to provide means for separating said feed-cups for the insertion and removal of the fabric sections, and means including a coiled spring surrounding said control-rod and bearing against said lever for biasing said feed-cups into work-clamping relation, the force exerted by said spring adapted to be regulated by the sleeve threaded into said machine-frame.

21. A sewing machine having, in combination, 50 a frame including a laterally projecting overhanging hollow bracket and a standard formed with an oil-tight lubrication compartment closed at its bottom by a detachable plate, two feed-cups exteriorly of and located beneath said overhanging hollow bracket, stitch-forming devices cooperating above the level of the feed-cups to seam fabric sections, a shaft depending from said overhanging hollow bracket and carrying one of said feed-cups, a second shaft carrying the other of said feed-cups, means operatively connecting said feed-cup carrying shafts to said main-shaft, a lever pivoted within said overhanging hollow bracket for supporting said depending feed-cup carrying shaft for limited movement toward and away from said other feed-cup, oil-sealing means in the form of a tubular sheath secured to the detachable plate of said standard and extending through said lubrication compartment and into said overhanging hollow bracket, a sleeve threaded into said detachable plate and extending into the lower end of said tubular sheath, a control-rod endwise slidable in said sleeve and connected to the lever pivoted within said overhanging hollow bracket, said control-rod adapted to provide means for separating said

feed-cups for the insertion and removal of the fabric sections, and means including a spring coiled about said control-rod for biasing said feed-cups into work-clamping relation, the force exerted by said spring adapted to be regulated by the sleeve threaded into said detachable plate.

22. A sewing machine having, in combination, a frame provided with a wall, an actuating shaft journaled in said frame, feed-cups located exteriorly of and supported by said frame adjacent said wall for sustaining and feeding fabric sections in a substantially vertical plane, stitch-forming devices including a needle and two oscillatable thread-handling implements, a reciprocating bar journaled in said wall and carrying said needle, supporting means for said oscillatable thread-handling implements including rock-shafts journaled in the wall in which said needle-carrying bar is journaled, said rock-shafts being relatively convergent toward the implements carried thereby, and means connecting said needle-carrying bar and said rock-shafts to said actuating shaft for imparting operative movements thereto.

23. A sewing machine having, in combination, a frame provided with a substantially flat vertical wall, feed-cups located exteriorly of and supported by said frame adjacent said flat vertical wall for sustaining and feeding fabric sections in a vertical plane, stitch-forming devices including a needle and two oscillatable elements, a bar carrying said needle and journaled for endwise reciprocation in said substantially flat vertical wall, supporting means for said oscillatable elements including shafts journaled in bearings provided in the substantially flat vertical wall of said frame above the level of said needle-carrying bar, said bearings having their axes disposed at an angle to one-another, means to confine said shafts against endwise movement, and means connecting said shafts and needle-carrying bar to said actuating shaft for imparting operative movements to said stitch-forming devices.

24. Stitch-forming mechanism for a sewing machine having a frame and a pair of feed-cups adapted for supporting and feeding fabric sections in a vertical plane, including, a needle, a bar carrying said needle and journaled for endwise reciprocation in a bearing provided in said frame, a pair of thread-handling implements complementary to said needle in the formation of stitches, carrier-members for said implements journaled in bearings provided in said frame at the same side of the vertical plane containing the fabric sections as is the bearing supporting said needle-carrying bar, said carrier-members being relatively convergent toward the implements carried thereby and confined to oscillatory movements about fixed axes, and actuating mechanism disposed within said frame for operating said needle and said thread-handling implements.

25. Stitch-forming mechanism for a sewing machine having a frame and a pair of feed-cups adapted for supporting and feeding fabric sections in a vertical plane, including, a needle, a horizontally disposed bar carrying said needle and journaled for endwise reciprocation in a

bearing provided in said frame, a pair of thread-handling implements complementary to said needle in the formation of stitches, carrier-members for said implements journaled in bearings provided in said frame above the level of and at the same side of the vertical plane containing the fabric sections as is the bearing supporting said needle-carrying bar, said carrier-members being relatively convergent toward the implements carried thereby and confined to oscillatory movements only about fixed axes, and actuating mechanism for operating said needle and said thread-handling implements.

26. A cup-feed sewing machine having, in combination, cooperating feed-cups between which the work passes, a frame having a wall at one side of the plane of the work passing between the feed-cups, stitch-forming instrumentalities including a needle and at least two thread-handling implements complementary thereto, an actuating shaft journaled in said frame, a needle-bar carrying said needle and having a right line movement through said wall of the frame, supporting rock-shafts for said thread-handling implements penetrating said wall of said frame and arranged angularly to each other, means connecting said needle-bar and said rock-shafts to said actuating shaft for actuation thereby, and means to confine said rock-shafts against endwise movement, whereby the extremities of said thread-handling implements operate in single planes only.

27. A cup-feed sewing machine having, in combination, cooperating feed-cups between which the work passes, a frame provided with a closed lubrication compartment having a wall at one side of the plane of the work passing between said feed-cups, stitch-forming instrumentalities including a needle and at least two other thread-handling implements cooperating therewith, an actuating shaft extending through said closed lubrication compartment, a needle-bar carrying said needle, rock-shafts supporting said thread-handling implements, said needle-bar and rock-shafts mounted in and passing through bushings in said wall of said lubrication compartment, means connecting said needle-bar and rock-shafts to said actuating shaft, and means to confine said rock-shafts against endwise movement, whereby the extremities of said thread-handling implements operate in single planes.

28. A cup-feed sewing machine having, in combination, a frame provided with a wall, an actuating shaft journaled in said frame, stitch-forming devices including a needle and two oscillatable thread-handling implements, a reciprocating bar journaled in said wall and carrying said needle, supporting means for said oscillatable thread-handling implements including rock-shafts journaled in the wall in which said needle-carrying bar is journaled, said rock-shafts being relatively convergent toward the implements carried thereby, means to confine said rock-shafts against endwise movement, and means connecting said needle-carrying bar and said rock-shafts to said actuating shaft for imparting operative movements thereto.

HANS HACKLANDER.
